United States Patent Office.

J. B. TUNSTALL, OF BOYDTON, VIRGINIA.

Letters Patent No. 83,424, dated October 27, 1868.

IMPROVED HYDRAULIC PRESS.

The Schedule referred to in these Letters Patent and making part of the same.

To all whom it may concern:

Be it known that I, J. B. TUNSTALL, near Boydton, in the county of Mecklenburg, and State of Virginia, have invented certain new and useful Improvements in Hydraulic Presses; and I do hereby declare that the following is a full, clear, and exact description thereof, reference being had to the accompanying drawings, and to the letters of reference marked thereon, which form a part of this specification, in which—

Figure 1 represents a vertical section of my improved hydraulic press, and

Figure 2, a side elevation of the same.

The object of my invention is to provide a convenient and simple hydraulic press, which shall be adaptable both to purposes of compressing various articles, and the elevating of weights; and to this end my improvement consists in providing the cylinder of the press with a cross-head, and suitably connecting with the same pivoted levers, which have upon their opposite ends toothed segments for working the platen of the pressing-device and the shaft of the weight-elevator.

In the accompanying drawings, which show a convenient arrangement of parts for carrying out the objects of my invention, A represents the frame of the machine, the lower part of which serves as a tank for containing the water used in its operation. A vertical cylinder, B, provided with a suitably-packed piston, is secured to the frame A, and has in communication with it a force-pump, b¹, operated by the lever b². The power of the machine can be proportionally increased by increasing the diameter of B relatively to b¹. The piston of the cylinder B is provided with piston-rods b b, to the upper ends of which a cross-head, D, is secured. The piston-rods b b move in guides in a supplementary frame, C, which is secured upon the top of the cylinder B, and held by the bolts c c.

The levers E E' are connected by links to the cross-head D, and have toothed segments upon their opposite ends. These levers are pivoted to the supplementary frame C, the relative lengths of their arms being proportioned according to the amount of pressure to be exerted.

A shaft, F, is mounted in bearings in the frame A, and has upon it a pinion, f', which gears with the toothed segment upon the lever E', and is likewise

provided with a pulley, f, to which a cord for elevating weights is attached.

A frame or press-head, G, moves vertically in guides in the frame A, and has secured to it a rack, g, with which the toothed segment on the end of the lever E gears. The weight of the press-head is counterbalanced by weights g', attached to cords passing over pulleys on the main frame. Platens of proper size and form can be attached to the press-head for the purpose of suitably effecting desired compression.

A single lever may be used for both pressing and elevating, when preferred, by having a number of holes therein, so as to vary the position of the fulcrum to suit the requirements of the work.

When the water from the tank is forced into the cylinder B by the force-pump b¹, it presses upon the piston thereof, and causes it to ascend, the pressure being as much greater than that applied to b¹ as the area of the cylinder-piston exceeds that of the pump. The cross-head D, in its ascent, draws up the inner ends of the levers E E', consequently forcing down the press-head and rotating the elevating-shaft. The cylinder B is to be provided with a suitable cock or valve for allowing the water to escape when the pressure is to be taken off.

It will be seen that power can be gained proportionally by increasing the lengths of the inner arms of the levers E E', and platens suitable to different kinds of work can be attached to the press-head G, according to convenience.

I do not broadly claim the several devices which go to make up the machine above described, either separately or in combination, for them I know to be old; but

What I do claim, and desire to secure by Letters Patent, is—

The arrangement, herein described, of cross-head D, attached to levers E E', by link-connection x, segment-gearing o o, rack g, press-head G, shaft F, pulley f, with its cord and weight, all constructed and operated as set forth.

In testimony that I claim the foregoing as my own, I affix my signature in presence of two witnesses.

Witnesses: J. B. TUNSTALL.
